ASBJORN SONSTHAGEN, OF WEST EALING, ENGLAND, ASSIGNOR OF ONE-HALF TO
EDGAR HUGH MORRIS, OF STONE NESS, KENT, ENGLAND

HIGH-SPEED REDUCING AND REFINING APPARATUS.

1,284,940.

Specification of Letters Patent. Patented Nov. 12, 1918.

Application filed July 24, 1917. Serial No. 182,426.

To all whom it may concern:

Be it known that I, ASBJORN SONSTHAGEN, a subject of the King of Norway, residing at West Ealing, England, have invented 5 certain new and useful Improvements in High-Speed Reducing and Refining Apparatus, of which the following is a specification.

This invention relates to an improved reducing and refining apparatus and particularly to the feeding devices for supplying material in an improved manner to the crushing rolls of reducing and refining apparatus, whereby the latter may advantageously run at high speeds.

An object of the invention is to provide a feeding device for combination with crushing rolls, wherein the material is carried by the feeding device in a layer of substantially 20 uniform and regulable thickness, and is removed therefrom directly by the crushing rolls, the arrangement being characterized by an even distribution of material upon the crushing rolls, whereby accumulation 25 and compacting of excess material between high speed crushing rolls is prevented.

Another object of the invention is to provide a feed roll arranged to revolve in such close proximity to a crushing roll and at 30 its meeting point with the latter to move in an opposite direction thereto that the film of material on the feed roll may be picked therefrom by the crushing roll, and a device movable toward and away from the 35 feed roll to coöperate therewith in regulating the thickness of the layer of material carried by the feed roll to the crushing roll.

A further object of the invention is to provide a feeding device of the class described 40 which comprises two feeding rolls rotatable in opposite directions and in close proximity to one another with means to vary the distance between the rolls to regulate the thickness of the layer of material 45 passing therebetween, each of said rolls arranged to revolve in close proximity to a corresponding crushing roll and to move in an opposite direction from its crushing roll at its point of contact therewith, and means 50 to move each feed roll toward or away from its respective crushing roll, the arrangement being characterized in that the material passes between the feed rolls without being crushed and is formed into a film or films 55 of regulable thickness, which film or films

are transferred to and by the crushing rolls while still in film form.

Other objects and advantages will appear in the description to follow and in the appended claims.

For the purposes of illustration, the invention, in a form at present preferred with detailed variations, is shown in the accompanying drawings, in which—

Figure 1 is a side elevational view of the 65 machine with parts broken away and shows the invention as applied to one type of refiner;

Fig. 2 is an end elevational view of a 70 part of Fig. 1;

Fig. 3 is a sectional elevation showing the 75 invention as applied to another type of refiner; and

Figs. 4, 5, and 6 are diagrammatical views showing modifications of the invention.

Referring to these drawings and particularly to Figs. 1 and 2 thereof, reference A indicates the frame of the machine in which are mounted crushing rolls 1, 2, and 3. The shafts for crushing rolls 1, 2, and 3 are indicated by references 4, 5, and 6, respectively, and from Fig. 2, it will be seen that shafts 4 and 5 and shafts 5 and 6 are connected by intermeshing gears. The shaft 4 is the main driving shaft of the machine and 80 may be driven by any suitable means not shown, the shaft being shown as broken off in Figs. 1 and 2. Shaft 4 is mounted in fixed bearings in frame A, but shafts 5 and 6 are mounted in slidable boxes 7 and 8, respectively. Each box 7 is movable by a screw 9 in an obvious manner and on the end of each screw is a worm gear 10. Each of the latter meshes with a worm 11 on a cross shaft 12, whereby, when the latter is 85 turned by the hand wheel shown, both boxes 7 are moved in unison to vary the pressure of roll 2 upon roll 1. The boxes 8 are similarly movable by screws 13. One of the latter is directly movable by the hand wheel 90 shown and the other screw is driven by a cross shaft 15 and suitable bevel gears, as indicated in Figs. 1 and 2. Thus, both boxes 8 may be moved in unison to vary the pressure of roll 3 upon roll 2.

The feeding device comprises a pair of oppositely driven rolls 16 and 17 mounted on shafts 18 and 19, respectively. Shaft 18 is mounted in boxes 20 which are slidably mounted in frame A and movable by screws 110

21 in an obvious manner. The feeding roll 16 is adapted to barely touch the crushing roll 1 and is adjustable relatively thereto in a general radial direction by the screws 21. 5 The shaft 19 of feeding roll 17 is mounted in boxes 22 which are slidably mounted in the outer ends of arms 23 and may be moved to various positions of adjustment by screws 24.

10 The arms 23 are loosely mounted on the shaft 5, one on each side of the crushing roll 2, as shown in Fig. 2. Each arm 23 is formed with a lug 25 in which an eccentric 26 is movable. Both eccentrics 26 are fixed 15 in spaced relation on a cross rod 27 and loosely mounted on the ends of the latter are links 28 which are pivoted to frame A at 29. A handle 30 is fixed to rod 27, whereby both eccentrics 26 may be simultaneously 20 turned to swing arms 23 on shaft 5 as a pivot. The eccentrics 26 are held in their various positions of adjustment in lugs 25 by frictional engagement with the latter but obviously may be held by any other suitable 25 means. It will thus be seen that feeding roll 17, which is adapted to engage crushing roll 2, is adjustable radially and circumferentially with relation thereto. The circumferential adjustment permits variations in 30 the pressure of roll 17 on roll 16 and the radial adjustment permits variations of pressure of roll 17 on crushing roll 2.

The shafts 18 and 19 are connected together at one end by intermeshing gears, as 35 shown in Fig. 2. Fixed on the other end of shaft 18 is a worm wheel 31 (shown as broken away in Fig. 1 to reveal the parts therebehind) which is driven by a worm 32 fixed on a shaft 33. The latter is mounted 40 in bearings secured to frame A and is driven from shaft 4 by the bevel gear connections shown in Figs. 1 and 2.

In order to supply material to the feeding rolls 16 and 17, a hopper 34, supported by 45 suitable brackets from frame A (Fig. 2), is arranged as shown in Fig. 1 to fit around the adjacent upper peripheral portions of the rolls. In certain instances, particularly when dry material, such as sugar, for example, is used, it may be desirable to provide a 50 preliminary grinding means to reduce the material to the requisite degree of fineness before it is fed to the rollers 16 and 17. Any suitable means may be employed to accomplish this function such as that illustrated 55 in the upper part of Fig. 1, for example. The grinding means shown in Fig. 1 is well known by those skilled in the art and will, therefore, be but briefly described herein. It 60 comprises a serrated roll *a* to which the material is fed by a hopper *b*. In cooperative engagement with roll *a* is a serrated plate *c* fixed to a lever *d* which is pivoted intermediate its ends at *e*. Lever *d* is movable by a 65 screw *f* to bring plate *c* into engagement

with roll *a* and a spring *g* holds the end of screw *f* against a channel *h* fixed to the supporting frame for hopper *b*. The material, after being crushed by roll *a* and plate *c*, falls upon a pivoted plate *i* and passes from the latter into hopper 34. The movement of material on plate *i* is facilitated by a vibratory movement imparted thereto by a ratchet *j* which cooperates with a pawl *k* on a rearwardly extending part of plate *i*. The 75 grinding device described has been merely shown in side elevational view in Fig. 1 and further illustration is thought unnecessary since the device is well known in the art. Any suitable means may be provided 80 for driving the roll *a* and ratchet *j* and these driving means have not been illustrated since they are unnecessary to an understanding of the invention.

The invention has been shown in Figs. 1 85 and 2, as applied to the usual type of three roll refiner wherein the delivery roll 3 is arranged at the bottom of the machine. The invention may be applied equally well to other types of refiners, as shown, for example, in Fig. 3. The refiner there shown comprises crushing rollers 1', 2', and 3', the latter being the delivery roll and arranged uppermost in the machine. The crushing rolls may be mounted and driven in any suitable manner or in a manner analogous to that illustrated in Figs. 1 and 2. The feeding rolls 16 and 17 are also mounted in a manner similar to that described. The roll 17 has been shown as engaging the first 95 crushing roll 1' and the roll 16 the second roll 2'. The roll 16 is movable radially to and from roll 2' while roll 17 is movable radially to and from roll 1' and also circumferentially with relation thereto.

Although the machine as heretofore described employs two feeding rolls which are separate and distinct from the crushing rolls, one of the latter, if desired, may be made to serve also as a feeding roll. Such an arrangement is illustrated diagrammatically in Fig. 4, wherein 35, 36, and 37 indicate the crushing rolls, the upper roll 35 being arranged to function also as a feeding roll and cooperate with a feeding roll 38. 100 The latter is preferably arranged to rotate at a higher speed than roll 35, and the speed of both rolls 35 and 38 is low as compared with the crushing rolls 36 and 37. The feed roll 38 is made radially and circumferentially movable with respect to roll 36 in a manner analogous to that already described in connection with roll 17.

A modification of the arrangement just described is shown diagrammatically in Fig. 5. 105 The crushing rolls are indicated by references 39, 40, and 41, and cooperating with the first crushing roll 39 is a feed roll 42. The latter alone is supplied with material from the hopper 43 and the regulation of 110

the feed to the roll 42 is obtained by an adjustable breast plate 44 mounted on the hopper. The feed roll 42 is made radially adjustable with relation to roll 39.

5 If desired, one of the feed rolls 16 or 17 may be stopped or its speed may be considerably reduced. This roll will then function as a breast plate and will have an action similar to that of plate 44.

10 In certain instances, it may be necessary to provide two or more sets of feeding rollers in one refiner. For example, if different materials are to be fed to the crushing rolls, such an arrangement is desirable.

15 In Fig. 6, a dual arrangement of feeding rolls has been shown in diagrammatical form. One pair of feeding rolls 45 and 46 feed one kind of material and the other pair of feeding rolls 47 and 48 feed another kind of material to the crushing rolls 49, 50, 51, and 52. The two materials are collected at the point 53 when they are mixed and pass together between the first pair of crushing rolls 49 and 50. Each feed roll in this arrangement is made movable toward and away from the crushing roll with which it cooperates, and the feed rolls of each pair are made movable the one relatively to the other to vary the distance therebetween.

20 The preferred operation of the machine will now be described. The material in hopper 34 passes between the feed rolls 16 and 17 and is fed to the crushing rolls. The rolls 16 and 17 move slowly compared with crushing rolls, and, as the material passes between the feed rolls, it is spread in a layer or film of substantially uniform thickness across the periphery of one or both of the feed rolls. The coating of the latter depends upon the viscosity of the material and upon the relative speed of the feed rolls.

25 Thus, where one of the feed rolls travels at a slightly higher speed than the other, which is the preferable arrangement, and a very viscous material is being treated, only one feed roll, the fast traveling one, will receive a coating. With a very liquid material, under the same conditions, both rollers will be coated, and, if the feed rolls run at the same speed, both will be coated irrespective of the degree of viscosity of the material. The feed rolls 16 and 17 are adjusted to barely touch the crushing rolls 1 and 2, respectively, and, as shown by the arrows, move in opposite directions to their respective crushing rolls adjacent their points of contact therewith. The film of material on one or both rolls is carried thereby until met by the oppositely moving portion of the crushing roll or rolls. The latter pick the film from the feed rolls and since they travel faster than the feed rolls, the film is drawn out by the crushing rolls into a still thinner film. The film or films of material is carried by one or both of the crushing rolls 1 and 2 to

their meeting point and is crushed therebetween and subsequently between the rolls 2 and 3 in the usual manner. The distance between the feed rolls 16 and 17 is variable by moving the pivoted arms 23 by means of handle 30 and thus the thickness of the film of material fed to the crushing rolls may be regulated as desired.

It will thus be seen that the feeding device described insures an even feed to the fast traveling crushing rolls and accumulations of material at the bight of the crushing rolls is effectually prevented. The feeding device is particularly important in high speed machines, since with the ordinary feed such machines have a tendency to choke up at the bight of the crushing rolls. The material accumulates between the rolls and is often compacted, whereby the crushing action is seriously impeded and in some instances stopped. Moreover, the material is burned when such accumulations occur and may in some instances even be fired by the friction created by the fast traveling crushing rolls. With the described feeding device, an even and regulable feed to the crushing rolls is obtained, and the material is distributed over a relatively large portion of the crushing rolls rather than localized as heretofore. The improved distribution of material to the crushing rolls is made possible by the arrangement whereby the material is taken directly from the feed rolls by the crushing rolls. Feed rolls have heretofore been employed in various forms in connection with crushing rolls, as I am aware, but the material with such feeding devices is allowed to drop from the feed rolls upon the crushers and is not directly fed thereto which is a distinguishing feature of the present invention. By reason of this feature, the crushing rolls can operate at higher speeds than heretofore and do more work in a better manner.

It is to be noted that it is not essential that two feed rolls be employed. The beneficial results above described may also be obtained with a single feed roll, which cooperates with one of the crushing rolls or with a movable breast plate as illustrated in Fig. 4, in which roll 35 is a crushing roll, and Fig. 5, in which 42 is the feed roll. The essential features of the feeding device are a feed roll arranged to revolve in close proximity to a crushing roll and so that the contacting portions of the feed and crushing rolls move in opposite directions, a means to move the roll to and from the crushing roll, and a part movable to and from the feed roll to coöperate therewith to regulate the thickness of the layer of material fed to the crushing roll.

The invention has been described in a preferred form with detailed variations for the purposes of illustration, but the scope of

the invention is defined by the appended claims rather than by the foregoing description.

What I claim is—

5. 1. A high speed reducing and refining apparatus, comprising, two or more crushing rolls, a feed roll arranged to receive the material and convey it in film form to a crushing roll, an adjustable device coöperating with the feed roll to regulate the thickness of the film, means to drive the feed roll at a speed less than that of said crushing roll and in a direction such that adjacent portions of said feed roll and crushing roll move in opposite directions, and means to vary the proximity of said feed roll and crushing roll, said feed roll being movable in such close proximity to said crushing roll that the latter directly removes the film from the former, the film removed from the feed roll being drawn out into a film of reduced thickness by the relatively fast traveling crushing roll.
2. A high speed reducing and refining apparatus, comprising, two crushing rolls revolute in opposite directions, feed rolls, one for each of said crushing rolls and each mounted to revolve with its periphery in spaced but close and regulable proximity to the periphery of its crushing roll, means to drive each feed roll at a surface speed less than that of the crushing roll with which it coöperates and in such a direction that the adjacent portions of the feed roll and crushing roll move in opposite directions, and means to supply material to the feed rolls, said feed rolls being also mounted so that their peripheries move in spaced but close and regulable relation, whereby each may coöperate with the other to regulate the flow of material therethrough, the space between the periphery of each feed roll and its crushing roll being no greater than that between the peripheries of the feed rolls, so that each crushing roll may directly remove a film of material from its feed roll, the film removed from the feed roll being drawn out into a film of reduced thickness by the relatively fast traveling crushing roll.
- 50 3. A high speed reducing and refining

apparatus, comprising, two crushing rolls revolute in opposite directions, a feed roll mounted to revolve in close and regulable proximity to one of said crushing rolls, a second feed roll mounted to revolve in close and regulable proximity to the other crushing roll, means to drive each feed roll at a surface speed less than that of the crushing roll with which it coöperates and in such direction that the adjacent portions of the feed roll and crushing roll move in opposite directions, means to supply material to said rolls, said feed rolls being also mounted in close and regulable proximity, and means supporting said second feed roll and mounted for movement in an arcuate path concentric with the second crushing roll, whereby the second feed roll may be moved toward or away from the first feed roll without varying the proximity of the second feed roll to its crushing roll.

4. A high speed reducing and refining apparatus, comprising, two oppositely revolute rolls so located with respect to one another that their peripheries are substantially in contact to perform a crushing operation, a feeding element movable in close proximity to one of said rolls and arranged to receive the material to be crushed and convey it in film form to said roll, a part mounted in close proximity to said element and coöoperating therewith to regulate the thickness of the film on the element, the space between said roll and element being no greater than that between the element and said part, whereby the film formed on said element is removed directly by said roll, and means to move said element at a surface speed less than that of said roll and in a direction such that adjacent portions of the roll and element move in opposite directions, said roll by its increased speed with relation to said element being arranged to draw out the film removed from the latter into a film of reduced thickness.
